UNITED STATES PATENT OFFICE.

RENE R. STUDLER, OF THE UNITED STATES ARMY, OF WASHINGTON, DISTRICT OF COLUMBIA, AND WILLIAM R. BLUEHDORN, OF HARTFORD, CONNECTICUT.

COMBINATION MOUNT FOR MACHINE GUNS.

Application filed April 28, 1927. Serial No. 187,370.

(GRANTED UNDER THE ACT OF MARCH 3, 1883, AS AMENDED APRIL 30, 1928; 370 O. G. 757.)

The invention described herein may be manufactured and used by or for the Government for governmental purposes without the payment to us of any royalty thereon.

5 The subject of this invention is a combination mount for machine guns.

For firing against ground targets a gun must be capable of being operated from a low stable mounting for the protection of 10 both the gun crew and advancing friendly troops while, for firing against rapidly moving aerial targets a high mount is of prime consideration to facilitate aiming and manipulation of the gun.

15 The employment of machine guns against aircraft having been successfully demonstrated this weapon is introduced into the anti-aircraft defense establishment. This development finds the organic infantry and 20 cavalry machine gun organizations equipped only with the low mounts and it is the purpose of this invention to provide the mount with an anti-aircraft adaptor in order that these arms of the service may employ their 25 weapon to the fullest advantage.

An adaptor to meet the requirements imposed by its assigned function should be a simple, compact, light and integral part of the mount, not interfering with ground firing, permitting a gun elevation of at least 30 80°, capable of being conveniently moved to and from operative position in a minimum time without disturbing the ammunition belt and without requiring handling 35 of the hot gun by the personnel and having sufficient clearance to permit efficient direction of fire. In addition to these requirements the adaptor must possess the characteristics of rigidity, stability and convenience in folding to the mount for transportation.

40 With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

45 A practical embodiment of the invention

is illustrated in the accompanying drawings, wherein:

Fig. 1 is a view in side elevation of a 55 mount showing the adaptor in lowered position during ground firing;

Fig. 2 is a similar view with the adaptor in position for anti-aircraft firing;

Fig. 3 is a rear end view of the adaptor; 60

Fig. 4 is a plan view of the lower member of the trunnion band;

Figs. 5 and 6 are detail views respectively in plan and side elevation of the clamping handle. 65

Referring to the drawings by numerals of reference:

The standard machine gun mount for low angle firing consists of a tripod 5 in whose socket is a pintle 6 which carries the cradle 7 by means of the trunnion 8. The gun is attached to the cradle by means of pins 9 and 10 respectively passing through the upper end of the elevating mechanism 11 and the aligned openings 12 in the forward 75 portion of the cradle.

The adaptor which is to be provided for permitting high angle firing against aerial targets comprises a bracket 13 mounted on cradle trunnion 8 and terminating at its free 80 end in an upwardly curved yoke 14, apertured to receive a trunnion band 15 embracing the water jacket of the gun and having its axis substantially in the plane of the axis of bore of the gun. The band is formed of 85 an upper and lower semi-circular member respectively designated as 16 and 17 and hinged as at 18. The clamping handle 19 is swung on a double eye bolt 20 carried by the lower member of the band and arranged 90 to enter the bifurcated lip 21 of the upper hasp member.

The function of the trunnion band is to support the gun when the adaptor is in the elevated position as seen in Fig. 2. In this 95 adjustment the gun has been moved forwardly in order to lock the band at the rear of the water jacket substantially at the center of gravity of the gun and it is clamped in place when the cleats 22 on the lower 100 member of the band are prepared to engage behind the water jacket.

In bringing the bracket to the elevated position the rear and forward gun attaching

pins 9 and 10 are removed and an upward pull on the gun causes the bracket 13 to swing about the cradle trunnion 8. The sides of the bracket are each formed with an angular extension 23 at their base and the alinement of apertures 24 therein with the opening 12 in the cradle enable the pin 10 to be reinserted and determines the upright position of the bracket.

10. When the gun is to be fired from the adaptor the cradle 7 may be swung to its position of maximum elevation in order to provide clearance. In preparing the mount for transportation the adaptor is swung rearwardly and nests on the cradle as indicated in dotted lines in Fig. 2. In an emergency the adaptor may be lowered to the position shown in Fig. 1 and firing may be commenced while the pins 9 and 10 are being 20 inserted in place.

I claim:

1. A mount for machine guns embodying a support, a cradle trunnioned on the support and having provision for attaching a 25 gun thereto, a bracket mounted on the cradle trunnion an upturned yoke on the free end of the bracket, a trunnion band mounted in the yoke and arranged to embrace the gun, means for clamping the band and means 30 for utilizing the gun attaching provision of the cradle in securing the bracket in upright position.

2. A mount for machine guns embodying a support, a cradle trunnioned on the support, a bracket mounted on the cradle trunnion, an upturned yoke on the free end of 35

the bracket, a trunnion band mounted in the yoke and arranged to embrace the gun, means for clamping the band and means for securing the bracket to the cradle in an upright position. 40

3. A mount for machine guns, embodying a support, a cradle trunnioned on the support, a bracket mounted on the cradle trunnion, means on the free end of the bracket 45 for supporting a gun and means for securing the bracket in a upright position.

4. A mount for machine guns embodying a support, a cradle trunnioned on the support and having provision for attaching a 50 gun thereto, a bracket having gun carrying means mounted for normal movement in elevation with the cradle and gun and means for securing the bracket against movement.

5. The combination of a machine gun and its mount, a bracket carried by the mount, a gun connection on the bracket, said connection in inoperative position of adjustment of the bracket engageable with the forward part of the gun and in operative 60 position of adjustment engageable with the gun and its center of gravity.

6. A mount for guns including means for trunnioning a gun for low angle firing and means for trunnioning the gun at a greater 65 height for high angle firing, said last named means permitting change from one position to another without breaking the connection between gun and mount.
